WILLIAM H. HEISE, OF LOS ANGELES, CALIFORNIA, ASSIGNOR TO BIG ROCK RANCH COMPANY, OF LOS ANGELES, CALIFORNIA, A CORPORATION OF CALIFORNIA

SELF-LEVELING PLATFORM OF A TILTED BODY

Application filed July 15, 1929. Serial No. 378,299.

My invention relates to hearses, and more particularly to the side-loading type of hearse which is now in extensive use. The side-loading hearse to which I refer has a 5 coffin-supporting platform or coffin dolly which is movable from a retracted position in the hearse to an extended position, in which position it extends outward from one side of the hearse body.

10 When such a hearse is disposed adjacent the curb of a crowned street, the hearse body is inclined to the horizontal and inclined to a horizontal sidewalk adjacent the curb. The inclination of the hearse body causes 15 the platform to be inclined so that the outer end is lowest. It is very difficult to load a horizontally-carried coffin onto an inclined coffin platform because the front end of the coffin contacts the top of the coffin platform 20 and prevents it from being moved over the top thereof. This is objectionable during a funeral as it creates confusion and mars the solemnity of the occasion.

It is an object of my invention to provide 25 a self-leveling platform for the body of a hearse which will occupy a substantially horizontal position regardless of the angularity of the road or the transaxial inclination of the hearse body.

30 It is another object of my invention to provide a means of retaining the platform in substantially horizontal position so that when it is extended out of the side of the hearse body, the weight of the casket placed 35 thereon will not cause the platform to move from horizontal. This clamping means is also of advantage in holding the platform stationary in the hearse body when the hearse is in motion.

40 It is a further object of my invention to provide a leveling means which is substantially self-leveling when the clamping means is released. This is of advantage since it allows the platform to be leveled automatically and then clamped in place.

Further objects of my invention will appear hereinafter.

In the accompanying drawings I have shown a preferred form of my invention.

50 In the drawings,

Fig. 1 is an end view of a hearse body showing the utility of my invention.

Fig. 2 is a partial sectional view taken on the line 2—2 of Fig. 1.

Fig. 3 is a plan view of the base of my 55 invention.

Fig. 4 is a section taken on the line 4—4 of Fig. 3.

Fig. 5 is a section taken on the line 5—5 60 of Fig. 4.

Fig. 6 is a plan view similar to Fig. 3 showing another clamping means of my invention.

Fig. 7 is a partial sectional view taken on the line 7—7 of Fig. 6. 65

Fig. 8 is an enlarged fragmentary sectional view taken on the line 8—8 of Fig. 6.

Fig. 9 is a fragmentary sectional view taken on the line 9—9 of Fig. 8.

Referring to the drawing, Figs. 1 and 2 show a hearse equipped with a device of my invention. In a floor 10 of the hearse body is a rectangular opening 11 in which a rectangular base 12 is positioned. At the ends of the base 12 and on a longitudinal axis 70 A—A thereof are secured supporting brackets 13 having axially projecting pins 14 which are rotatably supported in bearings 15 secured to the floor 10 of the hearse body for rotatably supporting the base 12 along the 75 axis A—A thereof.

Secured to the under side of the base 12 are four legs 17 of a pendulum formed integrally with a rectangular body 18 which 80 is held at a sufficient distance from the platform 12 to permit a drive shaft 19 of the hearse to pass therebetween. The body 18 is positioned below the center of the base 12 and the weight thereof acts as a pendulum to hold 85 the base 12 horizontal.

In order to lock the base 12 from movement relative to the floor 10, I provide lock means which I will now describe, having reference 90 to Figs. 3 to 5 inclusive.

Secured to the under face of the base 12 near one corner thereof, by bolts or lag screws 95 30 which extend through a wall 31, is an engageable member 32 of which the wall 31 is a part. The engageable member has an arc- 100

uated wall 33 which has an engagement face 34 generated around the axis A—A.

For gripping the engageable member 32, I provide a cam 35 which is secured on a 5 rotatable shaft 36, the shaft 36 being supported by bearings 37. The shaft 36 is rotated by bevel gears 38 and 39, the bevel gear 39 being secured to the lower end of a vertical shaft 40 which extends through the floor 10 and has an operating crank 42 secured to the upper end thereof. By operating the crank 42 the shaft 36 may be rotated to engage or disengage the cam with respect to the engageable member 32. If desired the face 15 34 and the periphery of the cam 35 may be roughened to increase the friction of the member 32 and cam 35.

When the clamping means is released the base 12 is free to rotate about the horizontal 20 axis A—A of the hearse body, and the body 18 being positioned below the center of the base 12 causes the base 12 to assume a horizontal position. The base 12 may then be clamped in this position by operating the 25 clamping means as previously described.

Carried by the base 12 is an extendible platform 45 which is movable from a position in the hearse with its major axis parallel to the axis A—A into a position with its axis 30 at right angles to the axis A—A as shown in Fig. 1. The platform may be so supported by rollers 46 of the platform which operate in slots 47 of the base 12.

In Fig. 1 the hearse is shown parked on a 35 crowned road 48 which causes the hearse body to decline to the right. If the base also declined, the platform when extended would decline as represented by dotted line 49 in Fig. 1, and the front end of a casket being 40 placed on the platform would engage it as represented by dotted lines 50.

In my invention this undesirable engagement is avoided by leveling the base 12 so that the platform 45 will extend in a 45 substantially horizontal plane.

Usually during transportation the base is locked to the floor 10. When the hearse is parked the clamp means is released and the body 18 causes the base to assume a level or 50 horizontal position. The clamp means is again caused to lock the base to the floor, and the platform 45 is extended from the side of the hearse ready to receive a casket 52. Since the platform is in a horizontal plane the front 55 of the casket 52 will not engage the platform at an angle but may be easily placed thereon.

In Figs. 6 to 9 inclusive, I show another form of clamping device 60 which is useful in clamping the base 12 to prevent rotation 60 thereof. The clamping device 60 is combined with a supporting means for supporting the forward end of the base 12 and comprises a supporting bracket 62 secured at the center of the forward end of the base 12 and having 65 an extending pin 63. The pin 63 is jour-

naled by a partial bearing 65 secured to the floor 10 and having a depending arm 67 pivotally connected thereto. A shoe portion 68 of the depending arm 67 engages the pin 63 with a clamping action when the arm 67 is rotated in a counter-clockwise direction as viewed in Fig. 8. The lower end of the arm 67 is formed into a fork 70 which engages flattened portions of diametrically opposite slots 71 in the surface of a nut 72 in a manner to prevent the nut 72 from rotating. The nut 72 is threadedly received on a transverse shaft 74 journaled by suitable bearings 75 on the under side of the floor 10, the extending ends of the shaft 74 being square to provide a means for securing an operating crank 77 thereon. An additional operating lever 80 on the shaft 74 extends into the driver's compartment and is operated by the driver. 75 80

In the operation of the clamping device 60, the shaft 74 is turned by the crank 77 or lever 80. The nut 72, being prevented from rotating by engagement of the fork 70 with the slots 71, is caused to move longitudinally of the shaft 74, thus pivoting the arm 67 and releasing or clamping the shoe portion 68 against the pin 63 so as to permit or prevent rotation of the base 12. 85 90

I claim as my invention:

1. In a hearse, the combination of: a body having a longitudinal axis; a platform normally disposed within said body and movable about said axis; means for laterally swinging said platform to a transverse position relative to said hearse, said axial and said lateral movements of said platform being independent; and locking means for arresting said axial movement of said platform in any one of a plurality of positions relative to said axis. 95 100 105

2. In a hearse, the combination of: a body having a longitudinal axis; a base member in said body adapted to move about said axis; a platform associated with said base member and laterally movable from a position in which it is parallel with said axis to a transverse position relative to said axis; and locking means for arresting the axial movement of said base member in any one of a plurality of positions relative to said axis. 110 115

3. In a hearse, the combination of: a body having a longitudinal axis; a floor in said body; a base member in said body; pendulum means for controlling the movement of said base member about said axis; a platform associated with said base member and laterally movable from a position in which it is parallel to said axis to a transverse position relative to said axis; and means for arresting the axial movement of said base member in any position relative to said floor to which said pendulum means may move it. 120 125

4. In a hearse, the combination of: a body having a longitudinal axis; a floor in said body; a platform normally disposed within 130

said body parallel to and movable about said axis; means for swinging said platform to a transverse position relative to said axis; pendulum means for controlling the axial movement of said platform about said axis; and means for arresting the axial movement of said platform in any position relative to said floor to which said pendulum means may move it.

10 In testimony whereof, I have hereunto set my hand at Los Angeles, California, this 11th day of July, 1929.

WILLIAM H. HEISE.
